ADOLPH M. HOLSTEIN, OF SYRACUSE, NEW YORK.

Specification for Design.

Patented June 4, 1918.

Application filed May 2, 1917. Serial No. 166,044. Term of patent 3½ years.

To all whom it may concern:

Be it known that I, ADOLPH M. HOLSTEIN, a citizen of the United States, residing at Syracuse, in the county of Onondaga and State of New York, have invented a new and original Ornamental Design for a Border Ornament for Furniture, Caskets, and Interior and Exterior Decorations, of which the following is a specification, reference being had to the accompanying drawing, forming a part hereof.

The drawing is a face view or front elevation of my design for border ornament.

The design comprises a representation of a twisted serpentine band or ribbon interwoven with twigs, leaves, buds, and flowers

which form a symmetrical curve opposite to the curves of the band as represented, the ends of the band and the twigs terminating at the intersections thereof at each end of the border.

I claim:

The ornamental design for a border ornament for furniture, caskets, and interior and exterior decorations, substantially as shown and described.

In testimony whereof, I have hereunto signed my name, at Syracuse, in the county of Onondaga, and State of New York, this 27th day of April, 1917.

ADOLPH M. HOLSTEIN.
